ICE CREEPER

Earl D. Witmer, Alhambra, Calif.

Application September 17, 1938, Serial No. 230,437

8 Claims. (Cl. 36—62)

This invention relates to improvements in ice creepers.

The general object of the invention is to provide an improved ice creeper.

5 Another object of the invention is to provide an improved ice creeper including novel releasable attaching means.

10 A further object of the invention is to provide an improved ice creeper so constructed that the weight of the wearer is equally distributed on both the shoe and the creeper.

15 A further object is to provide an improved creeper having novel spring action gripping teeth.

20 Other objects and the advantages of this invention will be apparent from the following description taken in connection with the accompanying drawing, wherein:

Fig. 1 is a perspective view of a shoe with an ice creeper thereon embodying the features of 25 my invention;

Fig. 2 is a side elevation of the ice creeper shown as mounted on a shoe;

Fig. 3 is a section taken on line 3—3 Fig. 2;

25 Fig. 4 is a fragmentary section taken on line 4—4 Fig. 2;

Fig. 5 is an enlarged fragmentary section taken on line 5—5 Fig. 2;

30 Fig. 6 is an enlarged fragmentary side elevation showing the parts in position ready to be detached;

Fig. 7 is a side elevation of a modified ice creeper shown as mounted on a shoe;

Fig. 8 is a section taken on line 8—8 Fig. 7;

35 Fig. 9 is a section taken on line 9—9 Fig. 7; and

Fig. 10 is a fragmentary plan showing the blank from which the spring member is formed.

Referring to the drawing by reference characters I have shown my invention as embodied in 40 an ice creeper which is indicated generally at 10. As shown the ice creeper 10 includes a base 11 and a detachable spring gripping member 12. The base member 11 is suitably secured by rivets 11' to the instep 13 of a shoe 14 and preferably 45 adjacent to the heel 15.

The base 11 is preferably made of sheet metal and is provided with grooves 16 defined by downwardly extending flanges 17 and inwardly extending tongues 18. The forward ends of the 50 tongues 18 are bevelled as at 19. The tongues 18 are also cut away at each side as at 20 to provide slots as shown in Figs. 2 and 6.

The detachable spring member 12 comprises a plan securing portion 21, a downwardly extending looped portion 22 and a forwardly extending por-

tion 23. The extreme end of the curved portion 23 is provided with an arcuate portion 24 which slidably engages the shoe instep. A grip member 26 is secured to the member 12 between the portions 22 and 23. The grip member 26 includes 5 a body 27 having inwardly extending flanges 28 and 29 which partially surround and tightly engage the spring member 12. The member 26 also includes downwardly directed sharpened tongues 31 which are integral with the inner 10 ends of the flanges 28 and 29.

The upper end of the downwardly directed loop 22 is notched on both sides as at 32 to allow the securing portion 21 to freely slide within the grooves 16. A spring 33 secured by a rivet 34 to 15 the portion 21 is so arranged as to be in alignment with the slots 20 when the rear of the plate portion 21 contacts the heel 15. The portion 24 of the spring member 12 engages and slides along the shoe instep each time weight is 20 applied thus causing the spring member to have a tendency to flatten out; thereby distributing the weight on the heel, sole of the shoe and on the grip member 26.

To attach the gripping member 12 to the base 25 member 11 the portion 21 is inserted in the grooves 16 and moved rearwardly until the spring 33 contacts the bevelled portions 19 on the tongues 18. Further rearward movement of the spring member 12 will flex the spring 33 until it 30 slides along the lower surface of the tongues 18. At the rearward limit of its movement the portion 12 engages the heel 15, the spring 33 engages in the slots 20 thus securely holding the spring member 12 in position. 35

To remove the spring member 12 the spring 33 is gripped on both ends and pulled downwardly until the slots 20 are cleared after which the spring member 12 may be easily removed and carried in the pocket ready for use when desired. 40

In Figs. 7 to 10 I show a modified ice creeper 35 which includes a base 36 and a spring member 37. The base 36 is suitably secured to the instep of a shoe as by rivets 38 and is provided with downwardly directed flanges 39 from which 45 inwardly directed tongues 40 extend to form grooves 41.

The flanges 39 at their forward ends are notched to provide lips 42 which extend downwardly and which are bevelled at their outer 50 ends as at 43.

The spring member 37 includes a flat upper portion 44 with the rear thereof notched as at 45 to form a tongue 46 which is bent down between the tongues 40 as shown in the drawing. The 55

forward end of the spring member 37 is looped downwardly as at 47, thence rearwardly as at 48. A gripping device 49 is secured to the rearwardly directed portion 48 of the spring member. The gripping device 49 is similar in all respects to the gripping device 26 previously described and is held in tight engagement by the resiliency of the material.

A spring 51 is secured to the portion 44 by a rivet 52 and is so arranged as to engage the lips 42 to hold the spring member in position. In attaching the spring member 37 to portion 44 is shifted along the grooves 41 until the spring 51 engages the bevelled portions 43 and rides over these bevelled portions and springs into position as shown in Fig. 7 where it will be noted that the tongue 46 engages the heel 53 of the shoe 54.

From the foregoing description it will be apparent that I have invented a novel ice creeper which can be economically manufactured and which is highly efficient for the intended purpose.

Having thus described my invention, I claim:

1. In an ice creeper, a member having means thereon adapted to attach the same to a shoe, said member including an arcuate portion having a gripping spur thereon, said arcuate portion terminating in a free end portion adapted to engage the bottom of a shoe.

2. In an ice creeper, a clamping member, a gripping member detachably mounted on said clamping member, said gripping member including an arched portion having a gripping spur thereon, said gripping member including a forward end portion adapted to slidably engage the bottom of a shoe.

3. In an ice creeper, a member having means thereon adapted to attach the same to a shoe, said member including a resilient portion having a gripping spur thereon, said resilient portion terminating in an end portion adapted to slidably engage the bottom of a shoe.

4. In an ice creeper, a resilient one piece spring member having means thereon adapted to attach the same to a shoe, said spring member including an arcuate portion having a gripping spur thereon, said arcuate portion terminating in a curved end portion adapted to slidably engage the bottom of a shoe.

5. For use with a shoe including a body, a heel, a sole and an instep, an ice creeper, said

ice creeper comprising a base, means to rigidly attach said base to the instep of a shoe, said base including opposed, parallel grooved portions and a detachable spring member including a flat portion slidably fitting said grooves, means for detachably securing said spring member in place, said spring member including an arcuate portion and a gripping member on the lower part of said arcuate portion.

6. For use with a shoe including a body, a heel, a sole and an instep, an ice creeper, said ice creeper comprising a base adapted to be rigidly attached to the instep of a shoe, and a detachable spring member including a portion slidably fitting said base, means for detachably holding said spring member in place, said spring member including a downwardly directed portion and a gripping member on the lower part of said downwardly directed portion.

7. An ice creeper comprising a base member and a detachable spring member, said base member including opposed, spaced, parallel grooved portions having aligned notches intermediate their length and being bevelled at their forward ends, said detachable spring member including a flat upper body portion having parallel sides and of a width to slide within said grooved portions, said body portion having a spring thereon adapted to engage in said aligned notches, said body portion having a rear portion which is reduced in width and bent downwardly to form a tongue, said spring member including an arcuate portion extending forwardly from said tongue, the forward end of said arcuate portion including a bearing portion adapted to engage the bottom of a shoe and a gripping member on said arcuate portion, said gripping member having spurs thereon.

8. For use with a shoe including a body, a heel, a sole and an instep, an ice creeper, said ice creeper comprising a base, means to rigidly attach said base to the instep of a shoe, said base including opposed, parallel grooved portions and a detachable spring member including a flat portion slidably fitting said grooves, means for detachably securing said spring member in place, said spring member including a rearwardly directed end portion adapted to be disposed in advance of the shoe heel and having a gripping member thereon.

EARL D. WITMER.
